DESIGN FOR A FLUORESCENT STARTER SWITCH

Arthur A. Richardson, Cranston, R. I., assignor to
The Lloyd Products Company, a corporation of
Rhode Island

Application July 18, 1947, Serial No. 140,365

Term of patent 3½ years

(Cl. D26—13)

To all whom it may concern:

Be it known that I, Arthur A. Richardson, a citizen of the United States of America, residing at Cranston, county of Providence, State of Rhode Island, have invented a new, original, and ornamental Design for a Fluorescent Starter Switch, of which the following is a specification, reference being had to the accompanying drawing, forming a part thereof.

Fig. 1 is a top plan view showing my new design for a fluorescent starter switch;

Fig. 2 is a side elevation thereof;

Fig. 3 is an end elevational view thereof; and
Fig. 4 is a perspective view thereof.

I claim:

The ornamental design for a fluorescent starter switch, substantially as shown.

ARTHUR A. RICHARDSON.
